UNITED STATES PATENT OFFICE.

FRED E. GREENE, OF BERKELEY, CALIFORNIA, ASSIGNOR TO BESSIE B. GREENE, OF BERKELEY, CALIFORNIA.

MIXER FOR PAVING MATERIALS.

Application filed July 21, 1924. Serial No. 727,161.

This invention relates to mixers for use in mixing various ingredients of asphalt pavings and the like.

The object of the invention is to provide a mixer which will insure a proper and thorough agitation and commingling of the various ingredients in as short a time as possible. A further object is to provide for a proper heating or cooking of the materials while they are being mixed together. It is also an object of the invention to provide a mixer which can be utilized in connection with a portable paving plant, and wherein the mixed materials will be automatically discharged from the mixer and delivered to the desired location upon the roadway.

These objects I accomplish by providing a drum having a novel arrangement of vanes on its interior which are in the form of interrupted spirals. These vanes serve to mix the materials and move the materials longitudinally of the drum, first in a direction from the feed opening to the discharge opening and thence in an opposite direction, so that a thorough mingling and mixing of the ingredients is produced. The arrangement of the drum is such that the mixed materials gradually work towards the discharge opening by reason of gravity, and here special means are provided to discharge the mixed materials through an opening in the end of the drum. The drum is preferably provided with heating means, so that where asphalt paving is being prepared the materials can be brought to the proper temperature and delivered onto the roadway in heated condition.

One form which my invention may assume is exemplified in the following description and illustrated in the accompanying drawings, in which:

Fig. 1 shows a vertical longitudinal sectional view of a mixer embodying my invention;

Fig. 2 shows a sectional view on the line 2—2 of Fig. 1;

Fig. 3 shows an end elevation of the discharge end of the drum;

Fig. 4 shows a side elevation of the discharge end of the drum;

Fig. 5 shows a detail view partly in section, of the gate for closing the discharge opening;

Fig. 6 shows a detail view in section of the

spring means incorporated in the gate-operating mechanism.

55

As herein shown, the device comprises a drum 10 rotatably mounted upon rollers 11 by means of a track 12 at either end of the drum. The drum has a feed hopper 13 at one end, leading to a central opening in the head of the drum. There is a central discharge opening in the opposite end of the drum, normally closed by a gate 14 presently to be described.

On the interior of the drum I arrange an outer set of interrupted spiral vanes 15 and an inner set of interrupted spiral vanes 16. There are preferably four spirals or helixes in each set, arranged at quarter-points. Each helix or spiral is interrupted, leaving a succession of vanes which extend through an arc of approximately ninety degrees, successive vanes being spaced approximately ninety degrees apart. For convenience I have designated the four outer vanes adjacent the feed end of the drum, *a*, *b*, *c*, and *d* respectively; the next succeeding vanes adjacent the middle of the drum are designated *a'*, *b'*, *c'*, and *d'*, while those near the discharge end of the drum are designated *b''* and *d''*. It will be seen that vane *a'* is a continuation of the helix represented by vane *a*; *b'* is a continuation of the helix on which vane *b* lies, etc. The outer series of vanes have their helix winding in one direction, so that material is propelled from the feed end to the discharge end of the drum, and the inner series of vanes wind in the opposite direction, so that material is propelled from the discharge end towards the feed end.

70

75

80

85

90

The inner series of spiral vanes is similar in arrangement to the outer series; that is to say, there are four vanes designated *e*, *f*, *g*, and *h* respectively, set at quarter-points near the feed end of the drum and extending helically for about ninety degrees, with a space of approximately ninety degrees between successive vanes lying in the same helical path, said successive vanes being designated *e'*, *f'*, *g'*, *h'*, and *g''* and *h''*. At each series of vanes there are but two vanes lying adjacent the discharge end of the drum, on account of the necessity for the provision of two scoops 17, which serve to pick up the material and direct it to the discharge opening. These two scoop members are arranged

95

100

105

on opposite sides of the discharge opening and extend from said opening to the periphery of the drum, being concave in form and shaped so as to deliver any material falling thereon to the discharge opening.

The outer series of vanes 15 are secured in any desired manner directly to the interior wall of the drum, and the inner series of vanes are held in place by longitudinally extending bars 18, so that the vanes revolve in unison with the drum.

The gate which controls the discharge opening is rotatably mounted upon an elbow 19, as best shown in Fig. 5, so that said gate 15 when moved into closed position may rotate with the drum. The elbow is formed with a cross-rod 20 at its upper end, and said cross-rod is hingedly supported upon standards or framework 21. At one end of the cross-rod 20 is a crank 22, connected to a link 23, the link in turn being connected to a lever 24, said lever being provided with the usual rack and detent mechanism. Through this lever the gate may be moved into closed position or 25 swung upwardly to allow the materials to be discharged through the opening in the end of the drum. The link 23 is preferably provided with a spring connection 25, shown in detail in Fig. 6, so that yielding pressure may be 30 applied by the lever to close the gate. The advantage of this is to insure proper closure of the gate in case small rocks or unyielding objects should become lodged between the gate and the rim of the opening. Such rocks 35 or small objects will ultimately become dislodged, and thereupon the spring pressure will serve to force the gate into close engagement with the end of the drum.

The drum is preferably surrounded with a 40 casing 26 having a fire-box 27 in its bottom portion and a flue 28 at the top. Any suitable heating means may be introduced in the fire-box 27 for heating the contents of the drum.

In practice, the drum is preferably mounted 45 on a carriage as shown, for example, in my co-pending application filed of even date herewith. Thereby the operation of mixing and heating the materials can be carried on while the carriage is in motion, and the mixed 50 materials can be delivered to the roadway in situ.

In the operation of the mixing drum the 55 various ingredients such as aggregate, liquid asphalt, limestone, and the like, are fed to the drum through the hopper 13, and the outer series of vanes (assuming that the drum is

being rotated in the direction indicated by the arrow in Fig. 2) will serve to force the material slowly towards the discharge end of the drum, and at the same time these vanes 60 will thoroughly mix the ingredients together. When the materials reach the discharge end of the drum they are piled up against the end wall of the drum, so that the inner series of vanes will act on the materials 65 to stir them and move them slowly in an opposite direction longitudinally of the drum. The materials upon reaching the feed end of the drum will be piled up so that they are out 70 of the path of the spiral vanes, and thereupon they are free to move back towards the discharge end of the drum along the axis thereof. In this connection it should be borne in mind that the drum is preferably arranged on a slight incline, so that gravity will act to 75 assist in the final movement of the mixed materials towards the discharge opening. When the materials have thus been mixed and heated a sufficient length of time, the gate 14 is swung open and thereupon the scoops 17 80 act to direct the mixed materials out through the discharge opening in an obvious manner.

Various changes in the construction and arrangement of the several parts herein shown and described may be employed without departing from the spirit of my invention, as disclosed in the appended claim.

What I claim and desire to secure by Letters Patent is:

A mixer for paving materials and the like, 90 comprising a rotatable drum, a feed hopper at one end thereof, said drum having a discharge opening formed in its opposite end, a manually controlled gate for maintaining the discharge opening normally closed, a plurality of helically shaped vanes directed all in one direction and secured on the inner face of the drum, said vanes being arranged in spaced groups from end to end of the drum and each group containing a plurality of interrupted vanes, secondary groups of helically shaped vanes all directed in the opposite direction and each group containing a plurality of interrupted vanes, means securing the secondary vanes with relation to the first-named vanes in a concentric position within the first-named vanes, and a pair of opposed scoop-like members extending from the discharge opening to the inner face of the drum for directing mixed material towards the 100 discharge opening.

FRED E. GREENE.
